CLAIM

The ornamental design for a headgear and yoke assembly, as shown and described.

DESCRIPTION

FIG. 1 is a front, top, right perspective view of a headgear and yoke assembly, showing our new design;

FIG. 2 is a rear, bottom, left perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The dashed lines in the drawings show portions of the headgear and yoke assembly that form no part of the claimed design.

The references to “left,” “right,” “front,” “rear,” “top,” and “bottom” in the figure descriptions are not meant to require certain in-use orientation; the headgear and yoke assembly may be used in any suitable orientations.
